Attorney

UNITED STATES PATENT OFFICE

VICTOR H. HARBERT, OF CHICAGO, ILLINOIS, ASSIGNOR, BY MESNE ASSIGNMENTS, TO
ILLINOIS RAILWAY EQUIPMENT COMPANY, A CORPORATION OF ILLINOIS

BRAKE-HANGER SUPPORT

Application filed May 16, 1927. Serial No. 191,623.

My invention relates to means whereby the hangers of railroad car brakes are pendently secured to the truck frames so as to permit the necessary oscillatory movement thereof during brake application; the present invention being more particularly adapted to the closed link type of hanger.

One object of my invention is to provide a construction whereby a firm non-vibrating and non-chattering relation between the hanger supporting or keeper element and the truck frame is provided to overcome the wear resulting from the use of constructions of this general character.

15 The objects of my invention and its advantages will be readily comprehended from the detailed description of the drawing, wherein—

Figure 1 is a side elevation of an arm or projection integral with the truck frame (broken away) and a portion of the hanger.

Figure 2 is a vertical sectional view taken on the line 2—2 of Figure 1.

Figure 3 is a cross-section taken substantially on the line 3—3 of Figure 2 looking in the direction of the arrows.

Figure 4 is a view substantially similar to Figure 2, showing a modified form.

Figure 5 is a vertical sectional view substantially similar to Figures 2 and 4, but showing another modification.

In the particular exemplifications of the invention, the truck frame 10 is shown provided with an arm or extension 11 formed integral therewith and disposed in a direction transversely of the truck. The outer end of the arm 11 is enlarged on the wheel side thereof and provided with a pair of laterally disposed vertically spaced slots which are shown 40 preferably entirely through the rear wall or web of the arm, thereby providing the parallelly disposed portions 12, 13 and 14 arranged one above the other in spaced relation and connected at opposite sides by the webs 45 15, 15. The intermediate portion 13 is preferably of slightly shorter length transversely than upper and lower portions 12 and 14, as can be clearly seen in Figure 2. The slots intermediate of the portions are intended to 50 receive a clevis member or U-shaped strap 16

of such width as to fit comparatively snugly between the web portions 15, 15 as shown in Figure 3. With the clevis or strap of substantial width as shown in Figure 3, the closed end or loop portion thereof will provide the 55 necessary bearing for the link hanger 17; or a hanger supporting pin of a well known type of U-shape hanger is employed; the clevis thereof having a width substantially equal to the spacing between the sides of the hanger 60 17. As shown in Figure 2, the sides of the clevis straddle the intermediate portion 13 and are of thickness corresponding substantially to the distance between the respective portions 12, 13 and 14 so as to fit snugly there- 65

between. The clevis, which is preferably of a steel forging, adjacent to the closed or loop end thereof, is shown pressed or slightly offset to provide the inner shoulder portions 18 adapted to abut against the intermediate por- 70

tion 13 when the clevis has been completely inserted or forced into place. As the vertical dimensions of the loop portion of the keeper means or clevis is such that said loop portion 75

partially enters between the upper and lower arm portions 12 and 14 (which are longer than the intermediate portion 13), I show the clevis provided with the shoulders 18 formed to prevent the too far inward move- 80

ment of the keeper means or clevis which so might cause the hanger 17 being brought into binding relation with the arm portion 13 and prevent proper free movement of the hanger. The shoulder portions 18, at the same time, provide a partial closure for the inner side of 85

the loop and prevent a sliding movement in the clevis toward and away from the arm of the upper end of the hanger. The shoulders 18, however, are partially rounded to permit free oscillatory movement of the hanger 17 90

necessary during proper application and re- 95

lease of the brakes. These shoulders 18 pref- 100

extension 11. The slots in the three portions 12, 13 and 14, which are shown of different lengths, have their inner or rear sides arranged in vertical alignment, while the forward ends of the slots are made sloping inwardly toward the lower sides. That is to say, the slot 20 in the upper portion 12 is made of somewhat greater length than the slot 21 in the intermediate portion 13, while slot 21 is of slightly greater length than slot 22 in the lower portion 14. The slots in the clevis 16 may be slightly longer than the largest slot 20 in the upper portion 12.

These slots are intended to receive a locking key or wedge member 23 which is adapted to extend entirely through the upper and lower portions 12 and 14 as well as through the intermediate portion 13 and both sides of the clevis 16. The rear side or longitudinal edge 24 of the locking key or wedge member is vertically disposed, being perpendicular to the ends of the key, while the forward longitudinal edge 25 is made sloping in order to taper the key toward the lower end thereof, as clearly shown in Figure 2.

As shown in Figure 2, the rear vertical edge 24 of the key member 23 contacts with the inner ends of the slots 19 in the clevis 16, while the forward sloping longitudinal side 25 contacts with the forward sloping ends of the slots 20, 21 and 22 in the portions 12, 13 and 14, respectively, when the wedge member or key has been forced into place; the transverse dimensions of the wedge member 23 relative to the slots 20, 21 and 22 being such that the rear longitudinal side 24 of the wedge member will not be in contact with the rear ends of the slots 20, 21 and 22 while transmitting its wedging action to the clevis. This permits the clevis 16 to be completely forced into place or drawn into the slots until the shoulders 18 of the clevis 16 are in abutting relation with the intermediate portion 13.

In Figure 4 I show a modified form where in the arm 11 of the truck frame, like in the previously described construction, is provided with the laterally extending enlargement which is also slotted transversely like in the previously described construction so as to provide the portions 26, 27 and 28. These portions are substantially similar to the portions 12, 13 and 14, except that the forward ends of the upper and lower portions 26 and 28 on the opposing or inner faces are tapered or beveled as shown at 29 to provide a somewhat enlarged opening to receive the loop end of the clevis 30. The clevis 30, which is in general respects similar to clevis 16, except that the loop portion thereof is somewhat larger than the remainder of the clevis, thereby providing the projecting shoulder portions 31 which extend beyond the horizontal planes of the upper and lower legs of the clevis. The distance, vertically, between the shoulder portions 31, is slightly

less than the space between the sloping faces 29 of the portions 26 and 28, at the outer ends thereof, in order that the head or loop end of the clevis 30 may enter between the upper and lower portions 26, 28.

The portions 26, 27 and 28 are also each provided with a longitudinally disposed slots 20, 21 and 22, respectively; with the rear ends of the slots arranged in alignment, while the forward ends of the slots are made sloping downwardly and inwardly and each slot receding or becoming shorter toward the bottom portion 28. The legs or two sides of the clevis are also longitudinally slotted at 19, like clevis 16, in order that the key or wedge member 23 may be inserted through all of the slots. The relation between the rear ends of the slots 19 and the inner shoulders 18 of the clevis is such that the outer shoulder portions 31 of the head of the clevis will be drawn into wedging relation with the tapered or beveled surfaces 29, before the inner shoulders 18 of the clevis are in abutting relation with the intermediate arm portion 27; while the rear vertical edge of the key or wedge member 23 will be out of contact with the inner ends of the slots 20, 21 and 22, as shown in Figure 4. As a result of this construction the forcing or wedging action is transmitted to the clevis and cause it to be held firmly in position.

The wedge members 23 are preferably made of suitable metal which permits the lower tapered end to be bent laterally as shown at 32 after the key members have been driven through the slots to an extent where the head of the clevis is drawn between the portions 12 and 14 in the construction shown in Figure 2, or the shoulder portions 31 of clevis 30 are drawn into firm wedging relation with the sloping faces of the portions 26 and 28 shown in Figure 4.

In Figure 5, I show a modification of the manner in which the clevis is secured or locked in place so as to prevent all possibility of vibration or chatter. The arm 11 at its enlarged outer end is transversely slotted in the same manner as heretofore described, to produce the vertically spaced portions 33, 34 and 35; the slots receiving the legs or two sides of the clevis or keeper member 36 arranged in straddling relation with the intermediate portion 34. The clevis 36 is substantially identical with clevis 16, except that the sides or legs are provided with bolt receiving holes instead of slots; the bolt holes of the clevis registering with similar holes in the intermediate portion 34 and the lower portion 35, to receive the bolt 37. The upper portion 33 is provided with a larger and non-circular hole to receive the bolt-head 38, thus not only preventing rotation of the bolt, but placing the head into direct contact with the clevis 36.

In practice, the truck side frames and

therefore also the projecting arms 11 are usually of cast metal while the clevis consists of a suitable steel forging possessing more or less resiliency. It is apparent therefore that when the nut 39 is screwed up tightly on the bolt 37 against the lower portion 35 of the frame arm 11, the head 38 of the bolt will draw the sides of the clevis 36 into firm gripping relation with the arm portions and prevent vibration or chatter.

With the side frames of cast metal and the clevis consisting of a steel forging, the constant oscillations of the brake hangers causes the frame portions to wear which results in objectionable and serious play. With my constructions large bearing surfaces not only are provided between the elements, but the various methods of fastening the clevis in place will securely hold the latter in place; the fastening means being such that adjustments are possible to take up any possible wear that may result. This is quite essential in brake mountings or supports where improper wear cannot be permitted because such wear would allow the brake shoes to drop down too far and consequently prevent proper application of the brakes in keeping with the rules and requirements.

I have shown what are believed to be the best embodiments of the invention which have been described in terms employed merely as terms of description and not as terms of limitation, as structural modifications may be made without, however, departing from the spirit of my invention.

What I claim is:

1. A brake hanger support comprising, in combination with a brake hanger and an arm on a truck frame, the outer end of said arm being provided with a pair of vertically spaced slots, U-shape keeper means for pendently supporting the hanger, the sides of said keeper means being adapted to enter into said slots in straddling relation with the portion of the arm intermediate of said slots, the opposing faces of the two sides of the U-shape keeper means being provided with shoulders adapted to abut against the intermediate portion of the arm and prevent too far inward movement of the keeper means, the slotted arm portion and keeper means having openings adapted to register, and means insertible in said openings adapted to cooperate with the intermediate portion of the arm to produce a binding relation between the keeper means and said arm and to lock said keeper means in place.

2. In a brake hanger support, the combination of a truck frame provided with laterally disposed and vertically spaced openings, a brake hanger supporting member provided with spaced sides each adapted to enter one of said openings, the walls of said openings and the sides of said member having registering openings, and vertically adjustable means

insertible through the registered openings, cooperating with portions of the truck frame and adapted to take up wear between said member and the walls of the openings and maintain a binding relation therebetween.

3. In a brake hanger support, the combination of a truck frame provided with laterally disposed and vertically spaced openings, the top wall of the upper openings and the bottom wall of the lower opening being disposed outwardly beyond the wall between said openings, a U-shape hanger supporting member adapted to seat between said top wall and said bottom wall with the sides of said member straddling the wall intermediate of said openings, said walls and the sides of the member having registering openings, and adjustable means disposed through all of said openings for increasingly effecting a binding relation between said walls and said member.

4. In a brake hanger support, the combination of a truck frame provided with laterally disposed and vertically spaced openings, the walls above and below the openings being extended outwardly beyond the wall intermediate of said openings, a hanger supporting member having a loop portion and spaced laterally disposed portions arranged in straddling relation with the intermediate wall while the loop portion is adapted to enter between said upper and lower walls in bearing relation therewith, the walls and laterally disposed portions of the supporting member being provided with registering openings, and means disposed through said openings for locking said member in place, said means permitting adjustment for increasingly effecting a binding relation between the walls and said member.

5. In a brake hanger, the combination of a truck frame provided with laterally disposed and vertically spaced openings, the walls above and below said openings being extended outwardly beyond the wall intermediate of said openings, a U-shaped hanger supporting member adapted to enter between and be in bearing relation with said upper and lower walls while its sides are in straddling relation with the wall intermediate of said openings, the walls and sides of said member having registering openings, adjustable means insertible in said openings for increasingly effecting a binding relation between the walls and said member, and means intermediate of the loop end of said member and said intermediate wall whereby a bearing relation with the end of said intermediate wall is provided and binding relation between the brake hanger and said wall prevented.

6. A brake hanger comprising, in combination with a brake hanger and a truck frame having laterally disposed and vertically spaced openings, a hanger supporting member insertible in said openings and provided
